UNITED STATES PATENT OFFICE.

CARL C. PETERSON, OF CHESTER, PENNSYLVANIA.

GARMENT-CLASP.

1,355,416.

Specification of Letters Patent.

Patented Oct. 12, 1920.

Original application filed January 10, 1919, Serial No. 270,531. Divided and this application filed June 21, 1919. Serial No. 305,721.

To all whom it may concern:

Be it known that I, CARL CHRISTIAN PETERSON, a citizen of the United States, residing at Chester, in the county of Delaware and State of Pennsylvania, have invented certain new and useful Improvements in Garment-Clasps, of which the following is a specification.

This invention relates to garment clasps of that general class shown and described in my copending application filed in the United States Patent Office on the 10th day of January, 1919, under Serial No. 270,531, and of which the present application is a division.

The object of the invention is to provide a clasp of simple and durable construction capable of being readily attached to a suspension element and which will effectually grip a stocking or other garment to be supported without liability of tearing or otherwise injuring the fabric.

The invention further aims to provide a garment engaging clasp including a stationary member having a circumferential seating groove and a pivoted member coacting therewith and adapted to clamp the adjacent portion of a garment within said groove when the free end of the pivoted member is swung downwardly to operative position.

A further object is to provide means at the rear of the garment engaging clasp for preventing the latter from coming in direct contact with the leg of the wearer when the clasp is used in connection with a hose supporter.

A still further object is generally to improve this class of devices so as to increase their utility, durability and efficiency.

In the accompanying drawings:

Figure 1 is a perspective view of a clasp embodying the present invention showing the same attached to the suspension element of a hose supporter;

Fig. 2 is a front elevation of the clasp detached;

Fig. 3 is a transverse sectional view taken on the line 3—3 of Fig. 2;

Fig. 4 is a side elevation partly in section showing the pivoted clamping bail about to engage the upper edge of a garment.

Corresponding and like parts are referred to in the following description and indicated

in all the views of the drawings by the same reference characters.

The improved clasp forming the subject matter of the present invention is shown by way of illustration in connection with a hose supporter in which 5 designates the elastic supporting band, 6 the suspension element or pad and 7 the interengaging fastening devices for securing the ends of the supporting band in assembled position.

Depending from the lower end of the suspension element 6 is a plate 8 which constitutes one element of the garment engaging clasp, the other element of the clasp being in the form of a bail 9 the upper end of which is pivotally mounted in a suitable eye or loop 10 arranged on the outer face of the plate 8 as best shown in Fig. 4 of the drawings. The upper end of the plate 8 is provided with an opening 10' through which extends the reduced end of the suspension element or pad 6, the pad being secured to the plate 8 by stitching or otherwise, as desired. Projecting laterally from the outer face of the plate 8 is an enlargement 11 having its peripheral edge formed with a concave seating groove 12 adapted to receive the material of which the garment is formed when the clamping member or bail 9 is swung downwardly to lowered position. The lower end of the enlargement or projection 11 is preferably curved or rounded while the free end of the clamping bail 9 is correspondingly curved or rounded so as to conform to and fit within the seating groove 12. The plate 8 at the lower or curved portion of the projection 11 is preferably cut-away at 13 in order to lighten the same and arranged directly above the cut-away portion is a transverse reinforcing web 14 which connects the adjacent side walls of the projection 11 and serves to prevent spreading of the walls thereof. Arranged at the rear of the plate 8 is a backing strip 15 so as to prevent the clasp from coming in direct contact with the leg of the wearer when said clasp is used in connection with a hose sup-

porter. The plate 8 is formed with a plurality of laterally extending attaching eyes 16 and the backing 15 is preferably secured to the plate by stitching the eyes 16 thereto as best shown in Fig. 2 of the drawings. Projecting longitudinally from

the free end of the clamping bail 9 is a finger piece 17 by means of which the bail may be conveniently released from engagement with a garment when it is desired to 5 detach the clasp therefrom.

It will thus be seen that by positioning the upper edge of a garment over the projection 11 and swinging the free end of the clamping bail 9 downwardly, the material 10 at the upper edge of the garment will be forced within the seating groove 12 and in which position it will be securely clamped by engagement with the bail 9, which as shown in Fig. 3 of the drawings also enters 15 the seating groove 12. A clasp constructed in accordance with the present invention will effectually grip the upper edge of a hose or other garment so that the same may be conveniently supported from a suspension 20 element, without liability of tearing, fraying or otherwise injuring the fabric of which the garment is formed.

While the clasp is shown and described in connection with a hose supporter it will, 25 of course, be understood that said clasp may be used with equally good results for any other purpose for which it may be found desirable or applicable. It will furthermore be understood that the clasps may be 30 made in different sizes and shapes and nickelized or otherwise coated or ornamented to give the same a neat attractive appearance.

Having thus described the invention, what 35 is claimed as new is:

1. A device of the class described including a suspension element, a plate depending from the suspension element and provided with a plurality of attaching eyes extending 40 laterally from the marginal edge thereof, said plate being formed on one side thereof with a hollow projection provided with a circumferential seating groove, a backing strip, stitching passing through the 45 attaching eyes of the plate and engaging the backing strip, and a clamping bail pivotally mounted on the plate and having its free end formed with a continuous unbroken loop adapted when swung inwardly to force 50 the material of a garment within said seating groove at the sides and end of the projection.

2. A device of the class described including a suspension element, a plate depending from the suspension element and provided with a hollow lateral projection, the marginal wall of which is formed with a continuous concave seating groove, a rein-

forcing web extending transversely of the projection at the upper end thereof and spaced inwardly from the outer edge of said projection, and a clamping bail pivotally mounted on the plate above the projection and movable into engagement with a garment for clamping the latter within the 60 groove and against the outer edge of the projection at the sides and end of said projection.

3. A device of the class described including a suspension element, a plate depending 70 from the suspension element and provided at one end with an opening for the reception of the adjacent end of said suspension element, the other end of the plate being provided with a hollow projection, the side 75 and end walls of which are concavo-convex in cross section to form an exterior seating groove, a transverse reinforcing web connecting the convex walls of the projection and spaced inwardly from the outer 80 edge of said projection, an eye formed on the plate above the projection, and a clamping bail pivotally mounted in the eye and having its lower end continuous and provided with a finger piece, said clamping bail 85 when swung inwardly serving to force the material of a garment against the outer edge of the projection and within the seating groove thereof.

4. A garment engaging clasp including 90 a plate having its lower end curved and its upper end provided with means for attachment to a suspension element, a hollow projection extending laterally from one side of the plate and conforming to the curved 95 lower end thereof, the marginal edge of said projection being concavo-convex in cross section to form a circumferential seating groove, a transverse reinforcing web connecting the convex walls of the projection 100 and spaced upwardly from the curved end thereof and inwardly from the outer edge of said projection, said plate being provided with a transverse eye fitting within the upper portion of the groove of said projection, and a bail pivotally mounted in said 105 eye and having its lower end portion provided with a finger piece, said bail coacting with the groove in the projection for clamping a garment against the outer edge of the 110 projection and within the groove thereof when the bail is swung inwardly to operative position.

In testimony whereof I affix my signature.

CARL C. PETERSON. [L. S.]
